UNITED STATES PATENT OFFICE.

STANLEY S. JENKINS, OF BUFFALO, NEW YORK.

FOOT GRIP FOR INVALIDS.

Application filed May 14, 1923. Serial No. 638,691.

To all whom it may concern:

Be it known that I, STANLEY S. JENKINS, a citizen of the United States, residing at Buffalo, in the county of Erie and State of New York, have invented certain new and useful Improvements in Foot Grips for Invalids, of which the following is a specification.

Bed-ridden invalids require for comfort frequent changing of their position in the bed, and various mechanical appliances have been devised for supporting the invalid's knees in elevated position to relieve the tedium of lying prone for extended periods. Unless some provision is made for retaining the knees in elevated position, it is impossible for very weak patients to lie upon their back with their feet drawn up, for the reason that the weight of the bed clothes and the weight of the legs themselves cause the patient's heels to slip on the lower sheet, tending to straighten out the legs, which can be maintained in elevated position only with considerable effort.

My present invention aims to provide a device by which the patient's heels may be prevented from slipping on the sheet, thereby enabling him to maintain his feet in drawn up position without exertion and without the employment of cumberson supports or appliances, which in many instances contribute toward the discomfort of the patient; and furthermore, my device eliminates the production of sores on the patient's heels, which frequently result from prolonged slipping of the heels over the sheets.

For the purpose of facilitating an understanding of my invention, I have illustrated on the accompanying drawings preferred embodiments thereof, from an inspection of which, when considered in connection with the following description, the principles of my invention and many of its inherent advantages should be readily appreciated.

Referring to the drawings:

Fig. 1 illustrates the manner in which my invention is used;

Fig. 2 is a side elevation showing the application of my invention to an invalid's foot;

Fig. 3 is a face view of the grip shown in Fig. 2;

Fig. 4 shows a grip of modified shape;

Fig. 5 illustrates the employment of a modified form of the invention;

Fig. 6 is a sectional view on the line 6—6 of Fig. 2; and

Fig. 7 is a similar view of another form of the invention.

My invention contemplates the provision of a grip or pad, capable of being attached to the foot, and preferably to the bare heel, of an invalid, the grip having a roughened outer face so as to impart to it frictional qualities, which will cause the same to adhere to the bed sheet, and thereby prevent slipping of the patient's feet. While the grip may be made of emery cloth, sandpaper, or the like, I have shown, for illustrative purposes, in Figs. 1, 2, 3, and 6 a grip 8 comprising a disk made of suitable flexible material, preferably of rubber and fabric composition, corrugated or otherwise roughened on its outer face, as indicated at 9, and provided for ventilating purposes with 11. The grip is adapted for direct application to the patient's heel, and a preferred provision for attachment comprises a layer 12 of suitable adhesive, disposed upon the inner face of the grip, and by which the grip may be affixed directly to the bare heel. This adhesive may be applied to the grip in spaced spots, or may be spread over the entire inner surface of the grip, and preferably possesses 15 inherent antiseptic properties, and may, for instance, for this purpose comprise as one of its constituents zinc oxide. The apertures 11 provide for air circulation in order that the skin of the heel may not be injured by 20 long application of the grip thereto. The grip preferably has a textile fabric inner face to prevent direct contact of the rubber with the skin, and is preferably concavo-convex in cross-section to fit the contour of 25 the heel, as shown.

The grip may be made in various forms, and in Fig. 4 the grip 13, instead of being circular in contour, is somewhat elliptical in shape; otherwise it is substantially like 30 that shown in Fig. 3.

In Fig. 5 I have shown the grip 14 as attached to the heel by a string or tape 15, tied over the instep. In some instances this, or a strap and buckle, or a button, may 35 be preferable to the use of an adhesive for holding the grip in position.

In Fig. 7 a slightly modified form is disclosed wherein the grip 15' is somewhat concavo-convex in cross-section, adapted to ac- 40

commodate in the concavity a pad 16 of cotton or material adapted to be interposed between the heel and the grip. In this instance, the grip is attached to the heel by adhesive 17 applied only to the margins of the grip.

The structure, method of use, and the advantages of my invention should be apparent without further description, and obviously, the size, shape and structure may be varied within considerable limits without exceeding the scope of the invention, as defined in the appended claims.

I claim:

1. A foot grip for invalids, comprising a gripping element formed of flexible material roughened on its outer face for engagement with a relatively slippery surface and provided with ventilating perforations, and

means whereby said element may be securely attached to the bare heel of an invalid.

2. A foot grip for invalids, comprising, a gripping element shaped to conform to a portion of a human foot and roughened on its outer surface so as to cling to a relatively smooth surface, and means on the inner surface of said element whereby it may be secured to the foot.

3. A foot grip for invalids comprising, a gripping element of frictional material adapted to be positioned over a portion of the sole of an invalid's foot, and a plurality of means for securing said material to the foot against relative displacement with respect to the sole of the foot, whereby slippage of the foot upon a bed sheet is prevented.

STANLEY S. JENKINS.
